UNITED STATES PATENT OFFICE.

BURT GREENISON, OF NEW YORK, N. Y.

LOCK.

1,409,094.

Specification of Letters Patent.

Patented Mar. 7, 1922.

Application filed February 3, 1921. Serial No. 442,332.

To all whom it may concern:

Be it known that I, BURT GREENISON, a citizen of the United States, and resident of the city of New York, borough of Manhattan, in the county and State of New York, have invented a new and Improved Lock, of which the following is a full, clear, and exact description.

My invention relates to locks, and aims to 10 provide certain improvements in connection with the same.

It is a well appreciated fact that it has been customary to provide a lock mechanism serving to retract and project a bolt, such 15 lock mechanism being associated with one face of the closure to be locked. It has also been customary upon the other face, to provide a knob permitting of a manual retraction of the bolt without the necessity of utilizing a key.

These locks, while serving to a certain extent to prevent the opening of the closure by an unauthorized person, have nevertheless failed, in that any person familiar with 25 the operation of the lock would have too little difficulty in "forcing" the same. In some instances, it has not even been necessary to resort to this action, as a skeleton or duplicate key would permit of a ready opening of 30 the closure with which the lock is associated.

Having these and other defects in mind, I have constructed a lock by means of which primarily, the structure provided, will serve to reduce the risk of an unauthorized person 35 opening the closure, to a minimum.

This is to be predicated to the fact that my invention aims to provide means serving to effectually prevent a retraction of the bolt by means of even a skeleton or duplicate key, 40 and renders the same solely inaccessible aside from the fact that it holds the bolt against motion, and that the bolt is incapable of being forced to its retracted position.

Still another object of my invention is the 45 provision of a lock of the character stated, in which a special form of key will be necessary to effect an operation of the bolt, the appearance of this lock in no way differentiating from that of a conventional lock, so 50 that an unauthorized person would be led to believe that a conventional skeleton or master key would be capable of effecting an opening of the closure.

Further objects of my invention will appear in the annexed specification and draw-

ings which latter present one practical embodiment of my invention, and in which

Figure 1 is a sectional side view of a lock constructed in accordance with my invention.

Figure 2 is a sectional view taken along the line 2—2 of Figure 1.

Figure 3 is a sectional view taken along the line 3—3 of Figure 1.

Figure 4 is a face view of the rear of the 65 closure with which my improved lock is associated.

Figures 5 and 6 are perspective views of certain of the essential elements forming a part of my invention, and

Figure 7 illustrates my invention applied to a slightly different form of lock.

Referring now more particularly to Figure 3, it will be seen that the reference numeral 10 indicates the jamb, with which 75 the closure 11 co-operates in the usual manner. Contrary to the conventional construction, it will be noted that the keeper 12, does not provide an opening, but furnishes a socket 13, for the reception of the bolt 14, 80 such socket being preferably of the same material as the keeper 12, and also conveniently forming an integral portion of the same.

Thus it will be obvious that a jimmy would be incapable of being forced between the 85 closure 11 and jamb 10 for the purpose of engaging the rear end of the bolt 14 to effect a retraction of the same, but aside from this safe-guard, I provide structure serving to further prevent any retraction of the bolt 90 14 by an extraneous member, this structure being hereinafter more fully specified.

Referring now more particularly to Figure 1, it will be seen that the reference numeral 15 indicates a lock of any desired construction applied in the usual manner to the closure 11, and serving to permit of an authorized operation of the bolt 14. This lock, in the usual manner co-operates with a spindle 16 extending through the entire body 100 of the closure 11, and having a knob 17 secured to its outer end, which knob will permit of a rotation of the spindle 16 without the necessity of utilizing a key.

In connection with the elements 14 and 16, 105 attention is invited to Figures 5 and 6, in which it will be noted that the bolt also, contrary to the conventional construction, presents an opening 18 through its body, one of the longitudinally extending faces of this 110

opening being formed with a series of teeth 19 or other suitable elements co-operating with the teeth 20 of the spindle 16. Thus it will be noted, that a firm inter-engagement 5 of the spindle and bolt is permitted, and that a movement on the part of one will be effectually transmitted to the other, a displacement of the bolt with respect to the spindle being prevented.

10 Thus it will be seen that a novel construction is provided in that a positive co-operation between the spindle and bolt exists, the bolt in turn co-operating with the keeper 12 to prevent any forcing of the lock.

15 Now with a view of providing means serving to preclude any possibility of an unauthorized person utilizing a duplicate or master key, to effect an opening of the closure 11, it will be noted, reference being 20 had to Figures 1 and 2, that a plate 21 is firmly fixed to the closure 11, as at 22 and encircles the spindle 16. This plate provides, a notch or opening 23 directly underlying the knob 17, and it will be noted that 25 a spring pressed plunger 24 is associated with the knob and arranged within the body of the same at a point at which it will be capable of moving into the depression 23 when the bolt 14 is in fully projected position.

30 It will thus be seen that when the plunger is in the position indicated in dotted lines in Figure 1, that even a person provided with a key capable of effecting an operation 35 of the spindle 16, will be unable to effect a rotation of the spindle 16, and to provide means serving to permit of an operation of the plunger 24 only when it is desired, it will be noted that I preferably provide 40 an operating handle 25 affixed to the outer end of the same, such operating handle being capable of being turned and being adapted to rest in one of two slots, 26 or 27. It is to be noted that the base of these slots 45 or grooves lie in different planes, the said grooves being arranged at an angle with respect to each other. Thus upon the handle 25 lying in the slot 27, it will be seen that the plunger 24 will be held in its retracted 50 position, but that a person may lift and rotate the handle 25 and permit the same to move into the groove 26, which being of greater depth allows the outer end of the plunger to move to the position indicated in 55 dotted lines, thus effectually preventing any movement of the spindle 16 by any person without the plunger 24 being again retracted.

60 Referring now more particularly to the structure illustrated in Figure 7, it will be

seen that the same includes the bolt 14, providing teeth 19, and co-operating with a spindle 28, it being noted that the key slot 28 of the spindle 28 extends throughout the entire length of the same, and that contrary 65 to the utilization of the knob 17, a lock 30 is arranged at this point, which lock is a duplicate of the lock 15.

70 Thus it will be noted that the lock, constructed in accordance with this latter embodiment of my invention will provide the identical appearance of the customary lock, but in the event that a master or skeleton key is utilized, it will be appreciated that any retraction of the bolt 14 will be precluded, in that it will be necessary to utilize a key extending throughout the entire length of the door 29, and arranged with elements corresponding to the elements of the locks 75 15 and 30, with which it is to co-operate. 80

85 From the foregoing it will be seen that I have constructed a lock, which will, as nearly as possible, preclude an unauthorized person from manipulating the same, in that it will be virtually impossible to manipulate the bolt by a skeleton or master key, aside from the fact that the bolt is arranged in such a manner as to be inaccessible to the use of a jimmy, it being also noted that even if the same element should tend to effect a 90 retraction of the bolt 14 this will be precluded in that it will be impossible to return the spindle 16, thus virtually holding the bolt against movement.

95 It will further be appreciated that numerous modifications of structure may readily be resorted to within the scope of my claims:

1. A lock, including a bolt, a spindle co-operating with said bolt for effecting a movement of the same, said spindle extending transversely of said bolt and beyond the side edges thereof, a lock secured to one end of said spindle, a knob secured to the opposite end of the same, said knob being formed with grooves extending at angles to each other, and being of different depths, a spring pressed plunger secured to said knob, a plate encircling said spindle, a head secured to said plunger, said head being adapted to seat in either of said grooves and when lying in the deeper of the same extending into an 105 opening forming a part of said plate.

2. A lock including a bolt having an opening presenting a toothed portion, a spindle, an annular series of teeth forming a part of 110 said spindle, said latter teeth being adapted to coact with said first-mentioned teeth, and a lock forming a part of said spindle.
